UNITED STATES PATENT OFFICE

FREDERICK RETTENMEYER, OF MERIDEN, CONNECTICUT, ASSIGNOR TO THE NAPIER CO., OF MERIDEN, CONNECTICUT, A CORPORATION

DESIGN FOR A METAL LINK FOR JEWELRY

Application filed March 5, 1929. Serial No. 30,323. Term of patent 3½ years.

To all whom it may concern:

Be it known that I, FREDERICK RETTENMEYER, a citizen of the United States, residing at Meriden, in the county of New Haven and State of Connecticut, have invented a new, original, and ornamental Design for a Metal Link for Jewelry, of which the following is a specification, reference being had to the accompanying drawing, forming part thereof.

Fig. 1 is a face view of a metal link for jewelry, such as bracelets, necklaces, and ear-rings, showing my new design; and

Fig. 2 is a side view of the same.

I claim:

The ornamental design for a metal link for jewelry as shown and described.

FREDERICK RETTENMEYER.
